(54) **CANNON, TRAVERSE BOARD**

(76) Inventor: **William H. Bell**

William H. Bell
Patent
(357)

The Schedule referred to in this Patent and making part of the same containing a description in the words of the said William H. Bell himself of his Improvement in a traverse board for pointing Cannons.

On an oak board about two inches in width, and two or four inches in depth be nailed horizontally fast against the interior wall of a fortification (in which a gun is mounted on its carriage in battery) in such manner that when the axis of the carriage is perpendicular to the wall, the centre of the board shall be in the vertical plane through the axis of the carriage and shall be immediately over and almost touching the tongue of the carriage, and if the board thus nailed fast has its rear or extreme edge shaped into the curve described (while the carriage travels from the extreme right to the extreme left) by a high nail in the tongue of the carriage immediately below and almost touching the board. And if this circular edge of the board be divided into 15 or 20 principale divisions, and each principale part into as many subdivisions as may be convenient, then, by means of the gradations on this board, and the high edge of about 6 inches in length, inserted in the centre of this tongue, which points to the gradations, any position at which the gun stands, as to horizontal range or traverse, may be known to the Captain of the gun at a glance of the eye, since it will be indicated at once by the point of graduation on the board, at which the high point stands, which position we will suppose to be at the traverse 105° of the graduation — when if we suppose a battery of 10 guns

of a fortified place to have each of these gun carriages similarly supplied with two transverse boards, furnished with a corresponding graduation, so as plane, so that every gun in the battery, carry a single word of the Commanders before given the same angle of仰 (ouyou) to range, for example transverse 10°, and thus, if the object to be battery be fixed, and its position be maintained during the day, the fire may be continued by a dark gunner with unabated energy, during the whole night, or during the day through the combats, discontinued with such a current. Of the object be moving (as that of a frigate) in front of the battery of 10 guns, furnished as above, with transverse boards, graduated in such manner, that the fire of the battery shall converge to the same, so as to stop at a distance of 1110 yards. These by the aid of these boards, and of the motion of the said signal for pointing converge patented Decr 8th 1829. The commanders placed on the ramparts, where he can see the moving frigate, and the flight of his shot, will be enabled to follow the object, while his fire, converging upon him, and to make with whole force as he pleased, by giving orders to the right, or to the left, or further or nearer, to any desirable degree of ranging. By means of the converging fire, afforded by the boards, and the other invention referred to, the Commanders instead of being obliged to direct the fire to the various and conflicting views of the different Captains of Crew, will be enabled to apply the talents of the best gunner to the fire of all the guns, and may shew his shot (when the transverse is graduated so that they range 10° at 1000 yards) to strike upon the side of the frigate within the narrow space of 57 feet, in one yard's distance of being fired at random, and scattered over

over the whole ship, and at 800 yards, he may steer
them to strike within the space of 38 feet and at 900 to
1100 yards within the space of 19 feet and at 1000 yards
within the space of 57 feet. 20. 20.
